BY *Berryfield & Dyer*
ATTORNEY

UNITED STATES PATENT OFFICE.

WILLIAM M. LUNT AND ROBERT G. ROBINSON, OF STOCKTON, CALIFORNIA.

GREASE PUMP.

Application filed November 27, 1922. Serial No. 603,495.

To all whom it may concern:

Be it known that we, WILLIAM M. LUNT and ROBERT G. ROBINSON, residing at Stockton, county of San Joaquin, State of California, have invented certain new and useful Improvements in Grease Pumps; and we do declare the following to be a full, clear, and exact description of the same, reference being had to the accompanying drawings, and to the characters of reference marked thereon, which form a part of this application.

This invention relates to improvements in grease-pumps or grease guns as they are commonly known, and is especially designed as an attachment for use in connection with the pumps used with the "Alemite" and similar systems for forcing grease to various bearings of motor vehicles.

The principal object of our invention is to provide an attachment for the above specified purpose which will enable a very great pressure being put on the grease with a much smaller expenditure of physical effort than is now necessary to successfully force the grease to the parts to be lubricated. This latter feature alone will appeal to the users of such grease-pumps, especially those in service stations and the like, who are called upon to make frequent use of these pumps, the operation of which as at present constructed, is very tiring, especially if kept up for any length of time.

A further object is to construct the device in such a way that it is a complete and compact unit of itself, and as such may be attached to or mounted on the ordinary grease pump without making any alterations of any kind on the latter.

A further object of the invention is to produce a simple and inexpensive device and yet one which will be exceedingly effective for the purposes for which it is designed.

These objects we accomplish by means of such structure and relative arrangement of parts as will fully appear by a perusal of the following specification and claims.

In the drawings similar characters of reference indicate corresponding parts in the several views:

Fig. 1 is a side elevation of the attachment, showing the same as mounted on an ordinary grease-pump.

Fig. 2 is an enlarged section of the attachment. 55

Referring now more particularly to the characters of reference on the drawings, the numeral 1 denotes the barrel of an ordinary grease pump, which has at one end a nipple 2 provided for the purpose of connection to a hose, and at the other end a handle 3 by means of which the threaded stem 4, connected to the usual plunger inside the barrel, may be turned. This operation causes the plunger to be moved lengthwise of the barrel, forcing the grease out through the nipple 2. 60 65

Our attachment comprises an open-ended cylinder 5, having on one side, intermediate its ends, a tapped orifice 6, into which the nipple 2 is removably screwed. 70

In order to make a more substantial connection with the barrel 1, and to protect and remove some of the strain from the relatively weak nipple, the cylinder 5 is formed with a cup or hood 7 concentric with the orifice 6; this hood surrounds the exposed portion of the nipple and impinges against the end of the barrel 1 when the nipple is screwed tightly into the hole 6. This hood is of a length so as to engage the head of the pump, and limit the movement of the attachment as it is screwed onto the nipple 2 so that it will be impossible to get the end of the nipple projected into the cylinder 5 75 80 85 where it would interfere with the movement of the plunger 8 which, if such occurred, would render the device inoperable.

Slidable with a snug fit in the cylinder 5 is a plunger or piston 8, one end of which projects from the cylinder and is pivotally connected to a lever 9 which in turn is pivoted at its adjacent end on one end of a link 10, itself pivoted between lugs 11 formed integral with the cylinder on the side thereof 90 95 opposite to the member 7.

A lever of the second class, which is the most powerful, is therefore provided, the total length of said lever being so much greater than the distance between the fulcrum and load points that a very great pressure or leverage may be exerted on the plunger with the expenditure of but little physical effort on the part of the operator manipulating the lever. 100 105

The lever extends in a plane radially of

the barrel 1, and in operation, the operator grasps the barrel with one hand and the lever with the other, the action being very similar in this respect to the manipulation of

5 a pair of shears.

The end of the cylinder opposite the lever is tapped as at 12 to receive therein the threaded end of the plug or coupling member 13 of a hose 14, through which the

10 grease is forced to the part to be lubricated.

In operation, the lever is first manipulated to move the piston clear of the orifice 6 which contains the end of the nipple 2. The handle 3 is then rotated to force some of the

15 grease in the pump into the cylinder 5 and to also fill up the hose 14 at the beginning of operations. This will not require much effort, since the only resistance to the movement of the barrel plunger is the inertia

20 of the grease itself. When this is accomplished, the lever is moved in the opposite direction, causing the piston to move past and close the orifice 6, and force the grease previously injected into the cylinder and

25 hose along and out of the latter for a distance equal to the stroke of the piston.

The piston is then retracted, the handle 3 again turned to inject more grease into the cylinder, and the piston again forced down

30 on the new filling of grease.

From the foregoing description it will be readily seen that we have produced such a device as substantially fulfills the objects of the invention as set forth herein.

35 While this specification sets forth in detail the present and preferred construction of the device, still in practice such devia-

tions from such detail may be resorted to as do not form a departure from the spirit of the invention, as defined by the appended 40 claims.

Having thus described our invention, what we claim as new and useful and desire to secure by Letters Patent is:

1. A secondary grease pump for attachment to a primary grease pump having a reduced outlet nipple, the secondary pump comprising a cylinder with means moving through the cylinder to eject grease therefrom, the cylinder having an orifice in its side for threaded engagement with the nipple, a hood on the cylinder surrounding the orifice and of a length to engage the head of the primary grease pump and limit the threaded advance of the cylinder on the nipple and prevent the nipple from projecting into the interior of the cylinder. 45

2. A secondary grease pump for attachment to a primary grease gun having a reduced outlet nipple, the secondary pump comprising a cylinder with lever operated means moving through the cylinder to eject grease therefrom, the cylinder having a screw threaded orifice in its side for receiving the nipple of the primary grease gun, a hood rigid with the cylinder and spaced around the orifice and adapted to engage the end of the primary grease gun and relieve 50 the nipple of lateral strain when the lever is operated to eject grease from the cylinder. 55

In testimony whereof we affix our signatures.

WILLIAM M. LUNT.
ROBERT G. ROBINSON.
